UNITED STATES PATENT OFFICE

HIRAM S. SOMES, OF ATTLEBOROUGH, MASSACHUSETTS.

DESIGN FOR A BREASTPIN OR SIMILAR ARTICLE OF JEWELRY.

Specification forming part of Design No. **11,495**, dated November 4, 1879; application filed October 2, 1879.
[Term of patent 3½ years.]

To all whom it may concern:

Be it known that I, HIRAM S. SOMES, of Attleborough, in the county of Bristol and Commonwealth of Massachusetts, have invented and originated a Design for a Breastpin or other Article of Jewelry, of which the following is a full, clear, and exact description, reference being had to the accompanying drawing, making a part of this specification.

A designates the petals of a lily, secured to an annular base mounted upon or made with a stem, and expanded to present the appearance of a half-open flower, within the cup of which is represented a set-stone, B, secured by vertical brackets rising from the inside of the cup.

The petals of the design are to be made of any suitable substance and of any desirable color, and the set-stone is to be of any appropriate material used in the fabrication of jewelry.

What I claim as my invention is—

The design for a breastpin and similar article of jewelry, consisting of the representation of a half-open lily having the petals A and set-stone B, substantially as described, and shown in the accompanying drawing.

HIRAM S. SOMES.
